US0D1036643S

(12) **United States Design Patent** (10) **Patent No.:** **US D1,036,643 S**
(45) **Date of Patent:** **** Jul. 23, 2024**

(54) **ROTATING DIFFUSER**

(71) Applicant: **Enhong Jing**, Dongguan (CN)

(72) Inventor: **Enhong Jing**, Dongguan (CN)

(**) Term: **15 Years**

(21) Appl. No.: **29/929,335**

(22) Filed: **Feb. 21, 2024**

(30) **Foreign Application Priority Data**

Jan. 10, 2024 (EM) 015046994-0001

(51) **LOC (14) Cl.** **23-04**

(52) **U.S. Cl.**
USPC **D23/366**

CLAIM

The ornamental design for a rotating diffuser, as shown and described.

DESCRIPTION

FIG. 1 is a front perspective view of a rotating diffuser, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the rotating diffuser, which form no part of the claimed design.

1 Claim, 8 Drawing Sheets
